UNITED STATES PATENT OFFICE.

JAMES G. NOLEN, OF NEW YORK, N. Y., ASSIGNOR TO ROBERT L. McELROY, OF CHARLOTTESVILLE, VIRGINIA.

SIGNAL-ALARM DEVICE FOR SPRINKLER SYSTEMS.

Application filed November 11, 1925. Serial No. 68,434.

This invention relates to signal alarm devices for automatic fire sprinkler systems for giving or transmitting to a distant point a signal indicating that the sprinkler system 5 is in active operation, the invention relates particularly to safety means to prevent the giving of a false alarm by water hammer or other sudden rise of pressure in the system, though it is noted that the invention 10 is not limited to sprinkler systems, nor to valves, nor even in some respects even to signal devices.

One object of the invention is to provide an efficient device for disabling the 15 signal alarm when the latter would otherwise be set off by water hammer or the like.

Another object of the invention is to provide an efficient apparatus or device adapted to be actuated by increased pressure within 20 a pipe or other closed system for actuating an exterior signal or other device.

Another object of the invention is to provide an improved apparatus or device consisting of electric circuits which will operate only on the coincidence of two, but not 25 one, of certain predetermined contingencies.

Other objects of the invention are to improve generally the simplicity and efficiency of such alarm and safety devices and to provide 30 an apparatus of this kind which is reliable, durable, and economical to manufacture and operate.

Still other objects of the invention will appear as the description proceeds; and 35 while herein details of the invention are described and claimed, the invention is not limited to these since many and various changes may be made without departing from the scope of the invention as claimed 40 in the broader claims.

The inventive features for the accomplishment of these and other objects are shown herein in connection with a sprinkler system having a riser having therein a check valve 45 having a valve member and a projecting stem held raised by said valve member when closed. A pipe passed into said riser below the valve carries on its outer end a casing having a small vent communicating with the pipe. Said pipe also carries a bellows 50 in the casing communicating with the pipe and adapted when distended to raise a projecting lever. An electric means including a circuit closed by said stem and lever

when both are down at the same time brings 55 about the ringing of a bell if said stem is lowered by the opening of the check valve without the simultaneous raising of said lever, as by water hammer.

In the accompanying drawing, showing 60 by way of example, one of many possible embodiments of the invention.

The figure shows the complete apparatus, a portion of a sprinkler system being shown in elevation and partial vertical section, 65 said casing being in vertical section and the electric means in diagram.

My invention is shown in combination with a sprinkler system including a conduit or riser 10 and branch pipes 11 communicating therewith provided with sprinkler heads 12. A check valve interposed in said riser comprises a casing having therein a large valve seat 15 on which is pivotally mounted a valve member 16. 70

A resilient metal diaphragm 18 held by a flanged collar 19 on a plug bushing 20 in a lateral opening 21 of the casing, carries a threaded stem 22 passing through the diaphragm and held in place liquid tight by 75 a pair of nuts 23 clamping against the diaphragm. The inner end 24 of the stem engages under and is held down by the valve member 16, whereby when the valve member is raised, said diaphragm is slightly 80 buckled and said inner end is raised by the action of the weighted outer end 25.

A short horizontal exteriorly threaded pipe 28 is passed into said riser just below the check valve and has its inner end 90 cut off at an angle of about 45 degrees to form an upper hood portion 30 adapted to increase the water pressure in the pipe when the water surges upwardly in the riser as by water hammer or the like. 95

An inner casing head 31 provided with a tapped boss 32 screwed on a short distance on said pipe and having a small lateral pressure equalizing vent 33 not covered by the pipe, carries a casing body 35 having an intermediate partition 36 forming an inner bellows chamber 37 and an outer diaphragm chamber 38 both normally filled with water. 100

A strong flexible diaphragm 40 is disposed between the outer edge of the casing body and an outer casing head 41 held in place by screws 42. A packing strip 43

around the edge and margin of both faces of said diaphragm between the diaphragm and said body and outer head respectively seals the diaphragm and spaces it from the outer head.

8 A threaded lever 45 passing through a central opening 46 of the head, and a mid opening 47 of said partition and through the diaphragm 40, is held in place by nuts 10 48 turned tight against both faces of said diaphragm for sealing the lever in the diaphragm and is provided at the inner end with a vertical slot carrying a roller 49 engaged by the lower face of a cam lug 48' 15 centrally mounted on the outer closed end of a corrugated metal bellows 50 having its outer end closed and its inner end secured on and communicating with said boss 32, whereby to depress the roller and said inner end as the bellows is expanded under the pressure induced in the hood 30, thereby to raise the heavy outer end 51 of the lever 45.

20 A normally energized relay magnet 55 connected by conductors 56 and 57 in a closed series circuit with a constant current battery 58, normally holds raised a pivoted armature 60 adapted to engage a contact 61 when lowered thereby to ring an alarm bell 62 connected by conductors 63, 30 in series with said armature, said switch contact and a local cell 65, whereby when the magnet is energized the bell is silent and when the magnet is de-energized the bell rings.

35 Conducting contact plates 70 and 71 mounted on and insulated from the lower face of said weighted and heavy ends 25 and 51 respectively are adapted to engage pairs of contacts 72, 73 to form switches connected in series with each other by conductors 76, 40 77, 78 respectively connected to the conductors 56, 57, thereby forming a shunt around said relay magnet 55, whereby when both of said switches are closed at the same time, 45 the current is shunted around the magnet, the magnet is de-energized and the bell sounded.

50 The pressure equalizing vent 33 permits the entire filling of the casing with water from the riser and establishes equal static pressure within and without the bellows to prevent its rupture, but the vent is so small that sudden pressure within the bellows is not equalized. The sudden pressure within 55 the bellows distends the bellows and also to an extent presses out the diaphragm 40, but as the diaphragm is much larger than the head of the bellows the movement of the latter is much greater.

60 The operation of the system is as follows:

As shown in the figure, the end 51 of the lever 45 is normally depressed and the end 25 is normally raised, thus breaking the shunt circuit 76, 77, 78 permitting the battery 58 to energize the magnet thereby to

hold the armature 60 raised to prevent the ringing of the bell.

If a fire should cause the sprinkler heads 12 to discharge, the valve 16 would rise, thus permitting the end 25 to bridge the 70 contacts 72. As the raising of the valve 16 would cause no increased pressure in the lower part of the riser 10, there would be no distension of the bellows, and the end 51 would remain depressed, thus completing 75 the shunt 76, 77, 78 shunting the battery current around and de-energizing the magnet 55, thus causing the armature 60 to fall and the bell to ring.

If however, there should be water hammer 80 or other upward surge of water in the riser such as would cause the end 70 to bridge the contacts 72, it is not desired that the bell should ring, as this would be a false alarm. This is prevented as follows:—The 85 upward surge caused by the water hammer raises somewhat the pressure in the lower part of the riser, and to this is added in the pipe the pressure caused by the surging 90 water striking in the hood 30. These pressures cause the distending of the bellows 50, the depression by the cam lug 48' of the roller 49 and the raising of the end 51 and the breaking of the shunt 76, 77 and 78, thus preventing the shunting of the current 95 around the solenoid, thus preventing the de-energizing of the magnet and the ringing of a false alarm.

I claim as my invention:

1. In combination, a conduit; a check 100 valve therein having a valve member and a projecting stem held raised by said member when closed; a pipe passed into said conduit between the valve and the inlet end of the conduit; a casing having a vent communicating with said pipe; a bellows in the casing communicating with the pipe; a projecting lever raised by said bellows when distended; an alarm bell; and electric means including a circuit closed by said stem and lever when both are down at the same time, 105 for bringing about the ringing of said bell.

2. In combination, a casing; a riser; a check valve therein; a valve member; and an intermediately fulcrumed stem passing 115 liquid tight through said casing and engaging under said member; a pipe passed into said riser below the valve; a casing communicating with said pipe; a diaphragm across the outer end of the casing; a bellows communicating with the pipe; a lever passing through said diaphragm and movable by said bellows; a battery; a relay magnet in a closed series circuit with said battery; an alarm bell rung by said relay; 120 pairs of contacts engaged by said stem and lever respectively; and conductors connected to said contacts for forming a shunt around said magnet when said stem and lever are down at the same time.

3. In combination, a conduit; a check valve therein having a casing and a valve member; an intermediately fulcrumed stem passing liquid tight through said casing and engaging under said member; a disabling means actuated by pressure in said conduit between said valve and the source of supply of the liquid and including a projecting lever; an alarm bell; and electric means including a circuit closed by said stem and lever when both are in actuating position at the same time, for bringing about the ringing of said bell.
4. In combination, a conduit; an actuating device therein actuated by the flow of liquid in the conduit; a pipe passed into said conduit between said device and the source of liquid supply; a casing having a vent communicating with said pipe; a bellows in the casing communicating with the pipe; a projecting lever raised by said bellows when distended; a disabling means actuated by said lever and a signal operated by the actuation of said device and disabled by the actuation of said means.
5. In combination, a conduit; an actuating device therein actuated by the flow of liquid in the conduit; a pipe passed into said conduit between the device and the inlet end of the conduit; a bellows mounted on and communicating with the pipe; a lever raised by said bellows when distended; a disabling means actuated by said lever and a signal operated by the actuation of said device and disabled by the actuation of said means.
6. In combination, a riser; a check valve therein having a valve member and a projecting stem held raised by said member when closed; a pipe passed into said riser below the valve; a casing provided with a boss screwed on said pipe and having a vent not covered by the pipe; said casing having a partition having an opening therein and forming inner and outer chambers; a strong diaphragm secured across the outer open end of the casing; a lever passing liquid tight through said strong diaphragm; a bellows in said inner chamber mounted on and communicating with said pipe; a roller on the inner end of said lever; a cam lug on the bellows and engaging over said roller; and electric means including a circuit closed by said stem and lever when both are down at the same time, for bringing about the ringing of the bell.
7. In combination, a pair of actuating devices each comprising a movable member; a battery; a relay magnet in a closed series circuit with said battery; an actuating device actuated by said relay; pairs of contacts engaged by said members respectively; and conductors connected to said contacts for forming a shunt around said magnet when said members are in contact position at the same time.
8. In combination, a conduit; an actuating device therein actuated by the flow of liquid in the conduit and including a projecting stem; a disabling means actuated by pressure in said conduit including a projecting lever; a battery; a relay having a magnet in a closed series circuit with said battery; an alarm bell rung by said relay when the magnet is de-energized; conducting plates on the outer end of said stem and lever respectively; pairs of contacts engageable by said stem and lever; and conductors connected to said contacts for forming a shunt around said magnet when said stem and lever are down at the same time.
9. In combination, a casing provided with an inlet opening and a large opening, the casing being otherwise closed; a diaphragm secured across the large opening, whereby said casing is entirely closed except at said inlet opening; a movable element disposed across said casing between said openings; the active area of said diaphragm being greater than the area of said movable element; a member passing liquid tight through said diaphragm and moved by said element; and an alarm device controlled by said member.
10. In combination, a casing provided with an inlet opening and a large opening, the casing being otherwise closed; a diaphragm secured across the larger opening, whereby said casing is entirely closed except at said inlet opening; a movable member disposed across said casing between said openings; the active area of said diaphragm being more than twice as great as the area of said movable member; a stem passing liquid tight through said diaphragm and moved by said member; and an alarm device controlled by said stem.
11. In combination, a pipe; a rigid casing secured on said pipe and having a large opening therein; a diaphragm secured across the opening, whereby said casing is entirely closed against exterior communication except into said pipe; a member passing liquid tight through said diaphragm; an alarm device controlled by said member; and a bellows in said casing communicating with and mounted on said pipe and adapted to move said member; the active area of said diaphragm being about three times greater than the head of the bellows.
12. In combination, a casing provided with an inlet opening; a movable bellows member disposed across said casing between said opening and a wall of the casing; a lever passing liquid tight through said wall; an alarm device controlled by said lever; and a cam lug on said member engaging said lever.
13. In combination, a casing provided with an inlet opening; a movable bellows member disposed across said casing between

- said opening and a wall of the casing; a cam on said member; a lever passing liquid tight through said wall perpendicular to said member and moved by said cam; and an alarm device controlled by said lever.
14. In combination, a riser; a pipe passed into said riser; a casing provided with a boss screwed onto said pipe; a diaphragm secured across the outer open end of the casing, whereby said casing is entirely closed against exterior communication except into said pipe; a lever passing liquid tight through said diaphragm; an alarm device controlled by said lever; a bellows in said casing communicating and mounted on said
- 5 10 15
- boss; and a cam on said head engaging the end of said lever.
15. In combination, a riser; a pipe passed into said riser; a casing provided with a boss screwed onto said pipe and provided with a vent not covered by the pipe; a lever passing liquid tight through a wall of the casing; an alarm device controlled by said lever; and a bellows in said casing and communicating with and mounted on said boss and adapted to move said lever.

Signed at New York in the county of New York and State of New York this 10th day of November A. D. 1925.

JAMES G. NOLEN.
